FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR MANUFACTURING SHOE SOLES.

Application filed July 13, 1920. Serial No. 395,820.

This invention relates to the manufacture of shoe soles and more particularly to the making of what are known commercially as manufactured insoles.

5 Manufactured insoles for welt shoes commonly comprise two or more layers of suitably shaped sheet material secured together in face-to-face relation, at least one of the layers having a projection or sewing rib 10 formed thereon to which the upper materials and welt of the shoe are sewed. The object of the invention is to improve the machines that have been heretofore employed in the manufacture of articles of the type indicated 15 or others suitable for such purposes.

With this object in view, a feature of the present invention contemplates, in making an article of this type, means for forming a sole-portion by cutting a blank of substantially the shape of a sole from sheet-material, molding a projection, as a sewing rib, therein, and bringing another sole-portion into association with the formed portion, as by positioning the ribbed blank in face-to-face relation with a similarly shaped blank. In the illustrated embodiment of the invention, the sole-portions are pressed together, preferably by means arranged to shape the superposed blanks to fit the contour of a shoe-bottom, although this is not essential to the broader features of the invention.

Another feature of the present invention relates to a support movable to a plurality of operating positions and the delivery thereto 35 of a sole-portion which is formed at one position and further operated upon at another position. In this connection, sole-shaped blanks may be cut from sheet material in different locations, assembled in proper relation 40 to each other to form a sole, and pressed together.

A further feature resides in the assembly of sole-portions cut from strips of sheet material in such a manner as to eliminate waste 45 of the material. Waste may be avoided by cutting the blanks of sheet material from a strip having a portion about equal to the length of the portions and interlocking the cuts. That is, each successive sole-shaped cut 50 extends across the strip with its toe pointing in the direction opposite to the adjacent cuts. With this condition it is requisite, where pressure is to be applied to all the sole-portions in a constant angular relation, to rotate each al-

ternate blank in its own plane until its toe-end points in the same direction before depositing it to receive pressure. In its broad aspect, the invention therefore involves means for operating upon work-pieces in different angular relations to one another, and delivering them for another operation in the same angular relation.

In producing insoles, as for welt shoes, in accordance with this invention, all the portions thereof cut at one location have sewing ribs or projections formed upon them, and the blanks cut at another location are assembled on the unribbed faces of the ribbed blanks. The securing of these portions together is accomplished, as a feature of this machine, preferably by coating a side of one of the strips from which the portions are cut with an adhesive, normally inactive but which may be treated to become effective, and rendering it active after the assembly of the 75 cut portions, as by heating.

Other features of the invention which may or may not be used in connection with the features above referred to, will be herein-after described and claimed, the advantages 80 of which will be obvious to those skilled in the art.

The several features of the present invention will be clearly understood from the following description and accompanying drawings illustrating a particular machine, in which:—

Figure 1 is a front view of said machine; Fig. 2 is a plan view of the upper portion of the machine; Fig. 3 is a detail side elevation of the press die; Fig. 4 is a detail plan view of a portion of the blank cutting and transferring mechanism; Fig. 5 is a diagrammatical view illustrating the operation of the mechanism of Fig. 4; Fig. 6 is a sectional 95 plan view taken on the line 6—6 of Fig. 1; Fig. 7 is a side elevation of the clutch and its actuating mechanism; and Fig. 8 is a sectional plan view of a portion of the mechanism for actuating the blank cutting mechanism.

While the machine hereinafter described may be employed in making manufactured soles of two or more layers of material, it has been found in commercial practice that 105 satisfactory results have been obtained from a three layer sole. Accordingly, an apparatus for manufacturing a three layer sole has

been shown in the drawings for the purpose of explaining the invention, but with no intent of limiting the invention to the particular type of sole except where so distinctly 5 stated in the appended claims.

In the illustrated embodiment of the invention a three layer insole composed of an intermediate layer of fabric or a leather substitute such as fibre, and outer layers forming 10 the sewing and sock surfaces, of canvas and leather skiving respectively, is being manufactured. The stock from which the component layers of the insole are formed may be supplied to the machine from strips 15 of the material which are wound in rolls, the intermediate and leather skiving strips being previously cemented together in face-to-face relation to form a single compound strip. The roll of canvas, and the roll forming 20 the compound strip are independently supported on the machine and are intermittently fed simultaneously over separate cutting blocks. Between the intermittent feeding movements of the strips, cutting dies 25 operate with the cutting blocks to cut progressively from the strips, blanks of substantially the shape of the insole to be formed. The blanks, as they are cut from the canvas strip, are severally transferred to a position 30 between male and female sewing-rib forming dies, and the blanks as they are cut from the compound strip are severally transferred to a position beneath a sole pressing die. After the sewing-rib forming dies have operated 35 on a canvas blank, the female die with the ribbed blank supported thereby is transferred to a position beneath the sole pressing die when it receives on its unribbed face a blank which has been cut from the compound strip. These dies then cooperate to 40 press the two blanks together and if desired, to mould them to the contour of the last bottom, thereby completing the formation of an insole. In order to secure the two 45 pieces of material together, the fibre or fabric side of the compound strip, before being wound and supplied to the machine, is coated with a prepared cement normally non-adhesive that becomes tacky upon the application 50 of a certain degree of heat. The sole pressing die is maintained at the proper temperature to supply such degree of heat to the adhesive coating and thus cause an adhesion of the two blanks during the pressure applying 55 operation. It has been determined that heat applied to the canvas blank during the sewing-rib forming operation will assist materially in the proper formation of the sewing-rib. Accordingly, means is provided for 60 heating the male sewing-rib forming die as well as the pressing die.

The illustrated machine is of the turret type and is adapted to make two insoles simultaneously. Accordingly, material is supplied 65 to the machine from two rolls of canvas strips

2 and two rolls of the compound fabric and leather strips 4 (Figs. 1 and 6). The several rolls of strips are mounted on brackets 690° apart secured to the base 8 of the machine, the brackets supporting the rolls of canvas strips 70 being located at opposite sides of the base, and the brackets supporting the rolls of fabric and leather strips being located at the front and rear of the base. The ends of the strips are drawn from the rolls over tables 10 (Fig. 1) 75 and cutting blocks 12, the tables being located between the rolls and cutting blocks and adjacent the latter. Each of the strips is fed over its supporting table and cutting block by means of a series of feed fingers 14 which 80 comprise pins secured to a sleeve 16 fixed on a horizontal pin 18 having its ends pivotally mounted in the upper ends of a pair of arms 20 (Fig. 6) located at opposite edges of the strip. The lower ends of the arms 20 are secured to the opposite ends of a rock shaft 22 85 journaled in the bracket 6. An arm 24 is secured to the outer end of the rock shaft 22 and is connected by a link 26 to the lower end of a vertically movable plunger 28 (Fig. 1) 90 mounted in another bracket on the base of the machine, the functions of which plunger will presently be described.

The supporting surface of the table 10 is curved lengthwise concentrically with the 95 axis of the rock shaft 22, and the points of the feed fingers 14 are held by gravity in engagement with the portion of the strip supported by the table. With this construction, it will be apparent that during a downward 100 movement of the plunger 28 the feed fingers will grip and feed the strip from the roll over the supporting table 10 and cutting block 12, and during an upward movement of the 105 plunger 28 the fingers will slide back over the strip. To enable the length of the feeding movement to be varied, the pivotal connection between the link 26 and the arm 24 is adjustable longitudinally of the arm (see Fig. 1). Each strip is held in position during 110 the retraction of the feed fingers 14 by means of a pair of stock grippers 30 comprising forwardly reaching arms pivotally mounted on opposite sides of the table 10 and provided with ratchet teeth 32 which are held in engagement with the strip by means of coiled springs 34 having their opposite ends attached respectively to the arms and cutting block support. The ratchet teeth are so shaped as to effectively hold the strip from 115 movement during the retraction of the feed fingers 14 and to permit the strip to freely move beneath the grippers as it is fed forward. The intermittent feeding movements of the four strips occur simultaneously, and 120 between such movements of each strip, its cutting block is forced upwardly to cooperate with one or the other of two cutting dies 36 and 38 to cut from the strip a blank of substantially the shape of the insole to be formed, 125 130

whereupon the cutting block is retracted and then the next feeding movement of the strip occurs. To enable the several cutting blocks 12 to be thus actuated, they are mounted upon 5 supports 37 at the upper ends of the plungers 28. The tables 10 move vertically with the blocks and are secured to vertical plates 39 projecting from the supports 37 beside the blocks (Fig. 1). The four plungers 28 are 10 mounted to slide in vertical bearings 40 formed in the ends of four bracket arms 42 secured to the base 8. The lower ends of the plungers 28 are pivotally connected to the upper arms of four toggles 44 (Fig. 1), the 15 lower arms of which are pivotally mounted on the base 8. The knees of the two opposite toggles associated with the mechanism for operating upon the canvas strips are connected by links 46 (Figs. 1 and 8) with lugs 48 20 on opposite sides of an eccentric strap that engages an eccentric 50 carried by a vertical driving shaft 52 extending through the center of the frame of the machine. The other two toggles are similarly connected by links 54 25 with lugs 56 on opposite sides of an eccentric strap that engages an eccentric 58 carried by the main shaft 52 below the eccentric 50. With this construction, it will be apparent 30 from an inspection of the drawings that during one rotation of the driving shaft 52, the four toggles will be straightened to simultaneously raise the plungers 28, and broken to simultaneously lower the plungers.

In order to adjust the cutting blocks to 35 compensate for wear, the plungers 28 have provision for vertical adjustment relative to their actuating toggles. Each of the plungers 28 is provided with a shank 60 that extends through the bearing 40 and is squared 40 to prevent the shank from turning in the bearing. The lower end of the shank 60 (Fig. 1) is provided with a socket 62 into which is screw threaded a sleeve 64 having a flange 66, in which are slant- openings, formed on 45 its lower end. A rod 68 is screw threaded into the sleeve, the lower end of which rod constitutes the lower end of the plunger. The rod 68 and the exterior of the sleeve 64 are oppositely threaded. It will be apparent 50 from this construction that by rotation of the sleeve 64 through the flange 66 the cutting block may be easily and quickly adjusted to the extent desired.

The cutting dies 36 and 38 of each of the 55 four sets are mounted on opposite ends of a turn table 70 (Figs. 1 and 6) that is journaled on the upper portion of a stud shaft 72 having its lower end secured in an aperture in the bracket arm 42. The dies are made of 60 bar stock, the die 36 being secured in an aperture of like configuration at one end of the turn table 70, and the die 38 being secured in a similar aperture in a disk 74 mounted on the opposite end of turn table. The machine 65 is illustrated in the drawings as stopped in

such position that the dies 36 are directly above the cutting blocks, and the dies 38 are directly above a series of four revoluble female sewing-rib forming dies 76. After the cutting blocks have been reciprocated to co- 70 operate with the cutting dies 36 to cut blanks from the four strips, the turn tables 70 are turned to reverse the position of the cutting dies 36 and 38, the blanks just severed remaining in the cutting dies 36 by frictional 75 contact therewith.

Adjacent the two stations where blanks are died out of the canvas strip and above the two female sewing-rib forming dies that may, at any cycle, be opposite these stations, 80 are two male sewing-rib forming dies 78 which are mounted for vertical reciprocation in the frame and do not follow the angular travel of the female dies with which they co- operate. Two sole pressing dies 80 are similarly mounted at the other two quadrants of the turret adjacent the two stations where blanks are died out of the fabric and leather strip. A detailed description of these dies 78 and 80 will be deferred until later. 90

Upon the coming into position, over the female dies 76, of the blank cutting dies 36 the four dies 78 and 80 move downward through the cutting dies 36 thus removing the blanks from the cutting dies and positioning them upon the female dies 76. During the actuation of the upper dies 78 and 80 the cutting blocks are raised to cut the next pieces from the strips.

In order to prevent waste of material, the 100 blanks are cut reversely in respect to their ends from each strip by the dies 36 and 38 in the manner shown in Figs. 4 and 6. Each cutting die 36 is positioned on the turn table with its heel end pointing outward and consequently the blanks cut by them have their heel ends adjacent the outer edges of the strips as indicated at *a*, Fig. 4. Since the cutting dies 38 must cut blanks with their toe ends adjacent the outer edges of the strips, as indicated at *b*, Fig. 4, the dies 36 and 38 must be brought over the strips in reversed positions, although they both are brought to a corresponding position over the female dies 76, the toe ends of which always point outward. To this end each disk 74 carrying a cutting die 38, is rotatably mounted in a circular aperture 82 in the turn table. The disk has a portion of smaller diameter which fits within the aperture and a portion of larger 110 diameter which forms a flange 84 (Fig. 1) that bears on the surface of the turn table surrounding the aperture. An arm 86 (Figs. 2 and 4) projects from the disk, the free end of said arm being provided with a roll 88 that 115 engages a straight groove in a bar 90 secured to the upper section 100 of the frame of the machine. With this construction, it will be apparent from an inspection of Figs. 4 and 5 that during the rotation of the turn table 70 120

the disk 74 will swing back and forth within the aperture 82 in such manner as to always maintain the toe end of the cutting die 38 pointing outward for its co-operation with 5 both the strips on the cutting blocks and the female dies 76.

As hereinbefore stated, the dies 78 and 80 are located directly above the series of four female dies 76, the dies 76 being equally 10 spaced about a turret 101 hereinafter described. In order that the dies 78 may co-operate with the pair of adjacent dies 76 to form sewing-ribs in the blanks cut from the canvas strips, these dies 78 are provided with 15 ribs 79 (Fig. 1) which are adapted to crimp the canvas and force it to enter grooves 77 formed in the dies 76. The dies 80 are adapted to cooperate with the pair of adjacent dies 76 to press the blanks cut from the fabric 20 and leather strips against the ribbed layer of canvas previously formed on the dies 76. As illustrated, all the dies are formed to mold the work and consequently the layers, as they are cut, are shaped to the surface contour of 25 the dies. To assist in the molding action of the dies 78 and 80, these dies are heated to a proper temperature by means of electric heating units 81 inserted in sockets therein. The heating of the dies 80 also causes the adhesive 30 coating on the fabric side of the fabric and leather blanks to be properly conditioned so that they will be securely attached to the canvas blanks upon operation of the dies 80. Upon retraction of the dies 78 and 80, the turret 35 101 is turned one quarter of a revolution to transfer the two dies 76 which have cooperated with the dies 78 in forming sewing-ribs in the canvas blanks, to a position beneath the dies 80. Likewise the two dies 76 40 which have cooperated with the dies 80 are positioned beneath the sewing-rib forming dies 78. During the movement of the turret 101, each turn table 70 is rotated one-half a revolution to present the next blank cut 45 from the strips beneath the dies 78 and 80, respectively. At the completion of this movement of the turret, the dies 78 and 80 are again forced down upon the dies 76, the dies 80 removing the fabric and leather pieces 50 from their cutting dies and pressing them down upon the unribbed faces of the canvas pieces to complete the formation of the insoles, and the dies 78 cooperating with the two adjacent dies 76 to form sewing-ribs in 55 the canvas pieces which have been placed between them. This cycle of operation is repeated, it requiring two reciprocations of the upper dies to complete each sole. During each turning movement of the turret, the completed insoles may be removed from the dies 76 60 either by hand or automatically as by pneumatic means.

To compensate for the material taken up in forming the sewing-ribs in the canvas 65 blanks, the cutting dies at the canvas cutting

stations are shaped to produce a blank slightly larger about the forepart and shank than is required for the fabric and leather blanks. In consequence the canvas blanks and fabric and leather blanks are of the same size and 70 shape when assembled and no subsequent trimming operation is required.

The vertical location of the turn table carrying the cutting dies is such that it swings the dies alternately just beneath radially projecting brackets 98 of the upper frame section 100 which brackets are held rigid by long bolts 99 (Fig. 1) rising from the base of the frame. The brackets 98 take the thrust of the cutting blocks 12 when they are moved 80 upward by the toggle actuating mechanism.

Each of the dies 78 and 80 is secured to the lower end of a plunger 102 (Fig. 1) which is mounted to slide in a bearing 104 in the upper section 100 of the frame. The portion of the 85 plunger 102 that extends through the bearing is square in cross-section to prevent the plunger from turning, and the portion 105 of the plunger adjacent the upper end of the squared portion is cylindrical and passes 90 through a cylindrical socket in the under side of a block 108 and through a central bore in said block. The plunger is provided with a tail rod 110 extending from the upper end of the cylindrical portion 105, which passes 95 through and is guided by a bearing 114 on a bracket projecting from the upper section of the frame. An expansion spring 116 is coiled about the reduced portion 105 of the plunger and is housed within the socket of 100 the block 108, its lower end bearing on the upper end of the squared portion 102 of the plunger. The downward movement of the plunger under the influence of the spring 116 is limited by nuts 118 threaded on the shank 105 and engaging the top of the block 108. By adjusting the nuts 118 on the shank 105, the pressure exerted by the dies on the work may be varied as desired. The die carrying 105 plungers 102 are reciprocated by crank actuated links 122 having their lower ends pivotally connected with the blocks 108. The lower portion of each link 122 is bifurcated to embrace the block 108 and the ends of the arms of the link are provided with apertures 115 which engage pivot pins in the form of screws 124 threaded into the block 108. In order to prevent undue pressure on the pivot pins 124 during the work engaging movement of the dies, the extreme ends of the arms of the bifurcated link 122 engage shoulders 126 formed on the block 108.

The links 122 associated with the sewing-rib forming dies 78 are pivotally connected at their upper ends with cranks 128 formed on 125 oppositely disposed shafts 130 having their outer ends journaled in bearings 132 formed on brackets secured to the radial brackets 98 of the upper frame section and their inner ends extended through bearings 134 in said 130

upper section. The shafts 130 are driven by bevelled gears 136 secured on their inner ends, which gears engage a bevelled gear 138 carried by the central driving shaft 52.

5 The links 122 associated with the sole pressing dies 80 are pivotally connected at their upper ends with cranks 140 (Fig. 1) formed on oppositely disposed crank shafts 142 (Figs. 1 and 2) having their outer ends journalled in 10 bearings 144 formed on brackets secured to the upper section 100 of the frame and their inner ends extended through bearings 146 in said upper section. The crank shafts 142 are driven by bevelled gears 148 secured on their 15 inner ends which engage a bevelled gear 150 secured to the upper end of the driving shaft 52.

The female dies 76 are mounted on arms of the turret 101 which is journalled on a bearing sleeve 156 (Fig. 1) projecting downwardly from the upper section 100 of the machine frame and held from longitudinal movement by being interposed between a shoulder 158 formed on the upper section of the frame 25 and a shoulder 160 formed on the base 8 of the frame. The turret 154 is intermittently rotated in proper timed relation to the actuation of the upper dies 78 and 80 by means of an annular gear 162 (Figs. 1 and 6) secured by screws 164 to the under sides of the 30 arms of the turret, which gear is engaged by a driving pinion 166 secured on the upper end of a vertical shaft 169 which is journalled in a bearing formed on a bracket projecting from 35 the base 8.

The turn tables 70 also are actuated by the annular gear 162 which gear meshes with gears 170 (Figs. 1 and 6) secured to the lower ends of the elongated hubs of the turn tables.

40 The shaft 168 which actuates the turret 154 and the turn tables 70; and the shaft 52 which actuates the upper dies 78 and 80 and the feeding and cutting mechanisms are both driven from a continuously rotating driving shaft 172 journalled in a bearing in the base 8 and arranged in alinement with the shaft 168. The shaft 172 drives the shafts 168 and 52 through a clutch (Figs. 1 and 7) comprising a double driving clutch member 174 45 splined to slide axially on the shaft 172, a driven member 176 at the upper side thereof secured to the lower end of the shaft 168 and a driven member 178 at the lower side thereof loosely mounted on the shaft 172. The driven member 178 has a pinion 180 formed thereon that engages a gear 182 secured to the shaft 52. The driving clutch member 174 is adapted to be shifted into engagement with either of the driven members by means of a bell crank lever 184 pivotally mounted on a plate depending from one bracket 42, one arm of which lever carries a roll 186 engaging an annular groove formed centrally in the driving clutch member and the other arm of which carries a cam roll 188 that engages a

groove in a cam disk 190. The cam disk 190 is carried by a shaft 192 journalled in a bearing on the base 8 and is driven by a worm wheel 194 secured thereto which meshes with a worm 196 secured to the lower end of the 70 clutch shaft 172. Upon engagement of the low portion 198 of the cam groove with the cam roll 188, the driving member 174 of the clutch is slid upward on the shaft 172 into engagement with the driven member 176 and 75 these clutch members are held in engagement until the rotation of the shaft 168 has turned the turret 101 one quarter of a revolution and the turn tables 70 one half a revolution for the purposes hereinbefore described. Upon 80 engagement of the high portion 200 of the cam groove with the roll 188, the driving member 174 of the clutch is slid downward on the shaft 172 carrying it out of engagement with the driven member 176 and into engagement with the driven member 178. During the period 85 of this engagement of the clutch members 174 and 178 the rotation of the shaft 52 causes the cutting blocks to move upwardly to cooperate with the cutting dies, the feed fingers 14 to 90 retract, and the upper dies 78 and 80 to move downwardly to act on the blanks held within the cutting dies. With these parts in this position the clutch member is shifted to neutral position by engagement of the portion 202 of the cam groove with the cam roll 188, leaving the blanks under pressure. As 95 the high portion 204 of the cam groove is carried into engagement with the cam roll 188, the driving member 174 of the clutch is again 100 shifted into engagement with the driven member 178, whereupon the shaft 52 is further 105 rotated causing the cutting blocks to retreat, the feed fingers 14 to advance to feed the strips and the upper dies 78 and 80 to be raised. 110 The cam roll 188 immediately enters the low portion 198 of the cam again to repeat the cycle of operations.

The clutch is provided with means for preventing the driven members 176 and 178 of the clutch from turning when disengaged from the driving member. This means comprises a vertical slide bar 206 (Fig. 7) having its ends guided by bearings on a bracket 208 secured to the base 8 and provided with locking dogs 210 adapted to engage notches 212 and 214 in the driven members 176 and 178, respectively. The slide bar 206 is actuated by the bell crank 184, the connection between the bell crank and the slide bar comprising 115 an extension 216 of the horizontal arm of the bell crank, the end of which extension is engaged on opposite sides by the ends of set screws 218 threaded through lugs on the slide bar. By rotating the screws a fine adjustment of the movement of the bar 206 is obtained. With this construction, upon disengagement of the driving member 174 from the driven member 176, an upper locking dog 210 is brought into engagement with one of 120 125 130

the notches 212 in the driven member, and upon disengagement of the driving clutch member from the driven member 178, a lower locking dog 210 is brought into engagement 5 with one of the notches 214 in the driven member 178. In both Figs. 1 and 7 these parts are shown in a neutral position.

The clutch shaft 172 has a worm wheel 220 (Fig. 1) secured thereto which is driven by 10 a worm 222 secured to one end of a horizontal driving shaft 224 journaled in a bearing in the base 8. A pulley 226 (Fig. 6) is secured to the other end of the shaft 224 and is connected by a belt 228 with a pulley 230 carried by the shaft of an electric motor 232 15 which is controlled by a switch 234.

While it is preferred to employ the specific construction and arrangement of parts illustrated and described, it is to be understood 20 that this construction and arrangement is not essential except so far as specified in the claims and may be changed or modified without departing from the broader features of the invention. The method which this machine 25 may perform is made the subject of a divisional application Serial No. 249,476, filed January 25, 1928.

The nature and scope of the present invention having been indicated and a machine 30 embodying the several features of the invention having been specifically described, what is claimed as new, is:

1. A machine for making soles having, in combination, a pair of cooperating dies constructed to mold a sewing-rib in a sole blank, 35 a blank cutting die, means for feeding a strip of sheet material, means for causing said cutting die to cut a blank from said strip, and actuating means for said dies to first transfer the blank to a position between the rib molding dies and then mold a rib therein.

2. A machine for making soles having, in combination, a pair of cooperating dies constructed to mold a sewing-rib in a sole blank, 45 a blank cutting die, means for feeding a strip of sheet material, means for causing said cutting die to cut a blank from said strip and transfer it to a position between said rib molding dies, and means for closing said rib 50 molding dies on the blank by a movement of one of them through the cutting die.

3. A machine for making soles having, in combination, means for cutting a sole blank from a sheet, means for thereafter forming 55 a sewing-rib in the blank, and means for positioning the ribbed blank in face-to-face relation with another sole blank and for pressing the two blanks together.

4. A machine for making soles having, in 60 combination, independent means for cutting respectively two sole blanks from different sheets, and means for forming a sewing-rib in one of the blanks and for then positioning the two blanks in face-to-face relation 65 and pressing them together.

5. A machine for making soles having, in combination, means for feeding a strip of material longitudinally, a die for cutting a sole blank from the strip transversely of the strip, a pair of cooperating sewing-rib forming dies, and means for feeding the cut blank to a position between the dies and for then actuating the dies. 70

6. A machine for making soles having, in combination, a pair of cooperating sewing-rib forming dies, means for feeding a strip of sole blank material past one end of said dies, a turn table, a sole blank cutting die on said turn table, means for presenting the cutting die to the strip to cut blanks transversely therefrom, and means for rotating the turn table to transfer the cut blank between said sewing-rib forming dies. 75

7. A machine for making soles having, in combination, a pair of cooperating sewing-rib forming dies, means for feeding a strip of sole blank material past one end of said dies, a turn table, a sole blank cutting die on said turn table, means for presenting the cutting die to the strip in a position to cut 80 blanks transversely therefrom and similarly arranged with respect to the sewing-rib forming dies, and means for rotating the turn table to present the cut blanks to the sewing-rib forming dies in the same angular relation 85 as that existing when said blanks are cut. 90

8. A machine for making soles having, in combination, cooperating sole pressing members, means for feeding a strip of material, means for successively cutting sole blanks 100 from the strip, alternate blanks being cut from the strip reversely in respect to their ends, and means for successively delivering the blanks as they are cut between the pressing members with their ends in the same position with respect thereto. 105

9. A machine for making soles having, in combination, a pair of cooperating sewing-rib forming dies, a pressing member to co-operate with one of the dies, means for feeding a strip of material, means for successively cutting sole blanks from the strip, alternate blanks being cut from the strip reversely in respect to their ends, means for successively delivering the blanks between said dies with 110 their ends in the same position with respect thereto, and means for operating the dies to act on a blank thus positioned between them, for then positioning a second blank on the first while the first is supported by the die 115 that cooperates with the pressing member and for relatively actuating said supporting die and pressing member to press the blanks together. 120

10. A machine for making soles having, in 125 combination, a sewing-rib forming die and a pressing member, a rotatable turret, a second sewing-rib forming die mounted on the turret and adapted to be positioned beneath said first die, means for feeding two strips of 130

sole material, means for cutting a sole blank from one strip and for delivering the blank to a position between said dies, means for relatively moving the dies to act on the sole blank positioned between them, means for rotating the turret to position said second die with the ribbed blank supported thereby beneath the sole pressing member, means for cutting a sole blank from the other strip and 10 positioning it upon the ribbed blank, and means for relatively moving said second die and the pressing members to press the two blanks together.

11. A machine for making soles having, in combination, a pair of cooperating pressing members, means for heating at least one of the members, means for supporting two sole blanks, one of the blanks being coated on one side with a normally inactive adhesive rendered effective by heat, means for forming a sewing-rib in one of the sole blanks for then positioning both blanks between the pressing members with the coated side of the one blank inward, and for then actuating the pressing members to press the two blanks together and heat the cement.

12. A machine for cutting sole blanks from a sheet of material having, in combination, a cutting block, a turn table, a rotatable disk 30 mounted on one end of the turn table, a pair of cutting dies adapted to cooperate with the cutting block to cut sole blanks from a sheet placed on the cutting block, one of the cutting dies being mounted within said disk and the 35 other on the opposite end of the turn table, and means for simultaneously rotating the turn table and the disk to alternately present the cutting dies to the cutting block in reverse positions relatively to their ends.

13. A machine for making insoles having, in combination, a pair of cooperating sewing-rib forming dies, means for feeding a strip of sole blank material past the toe end of said dies, a turn table, a rotatable disk 45 mounted on one end of the turn table, a pair of sole blank cutting dies mounted at the opposite ends of the turn table, one being rotatable with said disk and the other being fixed to the turn table, means for presenting the fixed cutting die in position to cut a sole blank transversely from the strip with its toe end directed toward the sewing-rib forming dies and then rotating the turn table to transfer said cut blank to a position between the dies, and means for simultaneously 50 rotating said disk to present the other cutting die in position to cut a sole blank transversely from the strip with its toe end directed away from the sewing-rib forming dies.

14. A machine for making soles having, in combination, operating instrumentalities, a cutting block, means for feeding a sheet of material over the cutting block, a turn table, a pair of cutting dies mounted on opposite 65 ends of the turn table adapted to cooperate

with the cutting block to cut sole blanks from the sheet, and means for turning the table to position one of the cutting dies opposite the sheet of material and cutting block, for relatively actuating the cutting block and die to 70 cut a blank from the sheet, for turning the table to present this die with the cut blank held thereby to the operating instrumentalities and to present the other cutting die to a position opposite the sheet and the cutting 75 block in such a manner that upon actuation of the cutting block and this die a blank will be cut from the sheet in reverse position in respect to its ends to that of the preceding blank, and for then turning the table and this 80 die to present the die with the cut blank held thereby to the operating instrumentalities in the same position in respect to its ends as the other die was presented to the operating instrumentalities.

15. A machine for making soles having, in combination, a cutting block, a sole cutting die, a plunger for actuating the cutting block to cooperate with the sole cutting die to cut a sole blank from a strip, and means actuated 90 by the plunger for feeding the strip over the cutting block.

16. A machine for making soles having, in combination, a turret, a plurality of sewing-rib forming and pressing dies supported by 95 and equally spaced about the turret, a plurality of sewing-rib forming dies and a plurality of pressing members mounted with a single forming die and a single pressing member succeeding each other in alternation above said sewing-rib forming and pressing dies, means for moving the upper dies toward and from the lower dies, and means for rotating the turret between the movements of the upper dies to advance each 100 of the lower dies and position them alternately beneath the upper sewing-rib forming dies and the pressing members.

17. A machine for making manufactured insoles in multiple having, in combination, 110 a turret having mounted thereon four female sewing-rib forming dies movable in steps by the turret between rest stations, a pair of male sewing-rib forming dies and a pair of insole pressing members mounted above the 115 rest stations of said female dies, said male dies and pressing members alternating with each other, mechanism for rotating said turret intermittently in angular steps of 90° to present the female dies successively to the 120 male dies and pressing members, means for simultaneously cutting four insole blanks from sheet material and delivering them to said female dies when at rest, and means for actuating the male dies and pressing members 125 after such delivery, two laminated insoles being formed at each semi-rotation of the turret.

18. In a sole-making apparatus, means for cutting a sole portion from sheet material,

- and means for conveying another sole-portion into association with the cut portion while it is engaged by an element of the cutting means.
- 5 19. In a sole-making apparatus, means for cutting a sole-portion from sheet material and forming a projection thereon, and means for thereafter associating another sole-portion with the cut and formed portion. 70
- 10 20. In a sole-making apparatus, means for cutting a sole-portion from sheet material, means for thereafter forming a projection upon the cut portion, and means for associating another sole-portion with the cut and 75 formed portion.
- 15 21. In a sole-making apparatus, means for cutting a sole-portion from sheet material, and means for molding the cut portion to the general contour of a shoe-bottom and for 80 forming a projection thereon.
- 20 22. In a sole-making apparatus, means for molding a sole-portion to the general contour of a shoe-bottom and for forming a projection on said sole-portion, and means for 85 associating another sole-portion with the formed portion at the molding and forming means.
- 25 23. In a sole-making apparatus, means for molding a sole-portion to the general contour 90 of a shoe-bottom and for forming a projection on said sole-portion, means for associating another sole-portion with the formed portion, and means for molding the associated portions.
- 30 24. In a sole-making apparatus, means for cutting a sole-portion from sheet material, means for molding the cut portion to the general contour 95 of a shoe-bottom and for forming a projection thereon, and means for associating another sole-portion with the cut and formed portion. 100
- 35 25. In a sole-making apparatus, means for forming a sole-portion, means constructed and arranged to impart to another sole-portion a form different from that produced by the first-mentioned means, and means for conveying the formed portions into association with each other. 105
- 40 26. In a sole-making apparatus, means for forming a sole-portion, means for cutting another sole-portion from sheet material, and means for conveying the cut and formed portions into association. 110
- 45 27. In a sole-making apparatus, means for forming a projection upon a sole-portion, means for cutting another sole-portion from sheet material and for conveying it into association with the formed portion, and means for pressing the cut and formed portions together. 115
- 50 28. In a sole-making apparatus, plural means independent of each other for simultaneously cutting a plurality of sole-portions from sheet material, and means for associating the cut portions. 120
- 55 29. In a sole-making apparatus, means for cutting a sole-portion from sheet material, independent means for cutting another sole-portion from sheet material, and means for associating the cut portions. 125
- 60 30. In a sole-making apparatus, means for cutting a sole-portion from sheet material, means for thereafter forming a projection upon the cut portion, means for cutting another sole-portion from sheet material, and means for associating the cut portions. 130
- 65 31. In a sole-making apparatus, means for molding a sole-portion to the general contour of a shoe-bottom, and means for applying another sole-portion to the molded portion and molding the portions together.
- 70 32. In a sole-making apparatus, means for molding a sole-portion to the general contour of a shoe-bottom, means for forming another sole-portion and for associating it with the molded portion, and means for applying molding pressure to the associated portions.
- 75 33. In a sole-making apparatus, means for cutting a sole-portion from sheet material, means for molding the cut portion to the general contour of a shoe-bottom and for forming a projection thereon, means for cutting another sole-portion from sheet material, and means for associating said sole-portions and applying pressure thereto. 95
- 80 34. In a sole-making apparatus, means for forming a sole-portion, means for heating the forming means, and means for bringing another sole-portion into association with the formed portion. 100
- 85 35. In an insole-making machine, a member arranged to travel to a plurality of operating positions, a co-operating member at an operating position, said members being provided with means for forming a sewing rib in an insole-portion, and means for applying heat to said co-operating member during the formation of said portions. 105
- 90 36. In a sole-making apparatus, means for molding a sole-portion to the general contour of a shoe-bottom, means for applying another sole-portion to the formed portion and molding the portions together, and means for heating the molding means. 110
- 95 37. In a sole-making apparatus, a support movable to a plurality of operating positions, means for forming a sole-portion, there being provision for delivering the formed portion to the support at an operating position, and means for operating upon the delivered portion at another position. 115
- 100 38. In a sole-making apparatus, a support movable to a plurality of operating positions, means for forming a sole-portion, there being provision for delivering the formed portion to the support at an operating position, means for operating upon the delivered portion at such position, and means for operating upon the delivered portion at another position. 120
- 105 39. In a sole-making apparatus, a support 125

- movable to a plurality of operating positions, means for forming a sole-portion, the forming means being movable to deliver the formed portion to the support at an operating position, and means for operating upon the delivered portion at another position. 5
40. In a sole-making apparatus, a support movable to a plurality of operating positions, and means for forming sole-portions at plural positions, there being provision for delivering the formed portions to the support at such positions. 10
41. In a sole-making apparatus, a support movable to a plurality of operating positions, 15 means for forming sole-portions at plural positions, there being provision for delivering the formed portions to the support at such positions, and means for operating upon the delivered portions at each position. 15
- 20 42. In a sole-making apparatus, a support movable to a plurality of operating positions, means for forming a sole-portion, means for feeding material to the forming means, there being provision for delivering the formed portion to the support at an operating position, and means for operating upon the delivered portion at another position. 25
43. In a sole-making apparatus, a support movable to a plurality of operating positions, 30 means for forming sole-portions at plural positions, and means at each position for feeding material to the forming means, there being provision for delivering the formed portions to the support at such positions. 35
- 35 44. In a sole-making apparatus, means for cutting sole-portions, means for operating upon the cut portions, and means for moving the cutting means and operating means relatively to associate the cut portions with the operating means. 40
45. In a sole-making apparatus, means for cutting sole-portions, means for operating upon the cut portions, and means for moving the cutting means to deliver the cut portions to the operating means. 45
46. In a sole-making apparatus, means for cutting sole-portions, sole-molding means, and means for moving the cutting means to deliver the cut portions to the molding means. 50
- 50 47. In a sole-making apparatus, a plurality of cutting members movable to bring different members into cutting position, and means for operating upon the cut portions, the cutting members in their movement delivering the cut portions to the operating means. 55
48. In a sole-making apparatus, means for cutting sole-portions, means for operating upon the cut portions, means for moving the cutting means and operating means relative- 60 ly to associate the cut portions with the operating means, and means for moving the cutting means and operating means relative- ly to move the cut portions from the cutting means. 65
- 65 49. In a sole-making apparatus, means for cutting sole-portions, sole-molding means, and means for moving the cutting means to deliver the cut portions to the molding means, the molding means co-operating with the cutting means to remove the portions there- 65 from. 70
50. In a sole-making apparatus, means for cutting sole-portions, sole-molding means, and means for moving the cutting means and molding means relatively to carry the mold- 70 ing means through the cutting means to remove cut portions therefrom. 75
51. In a sole-making apparatus, means as- 75 sociated with a plurality of operating posi- tions for cutting sole-portions, means at each position for operating upon the cut portions, and means for moving each cutting means to deliver to the respective operating means. 80
52. In a sole-making apparatus, means as- 80 sociated with a plurality of operating posi- tions for cutting sole-portions, means at each position for operating upon the cut portions, means for moving each cutting means to de- 85 liver to the respective operating means, and means for thereafter moving the cut portion from one operating means to another. 85
53. In an apparatus of the class described, means for operating upon different work- 90 portions in different angular relations to one another, means for further operating upon such portions, and means for transferring the portions from one operating position to the other and delivering them to the latter in the same angular relation. 95
54. In an apparatus of the class described, means for forming different work-portions in different angular relations to one another, 95 means for further forming the formed portions, and means for transferring the portions from one forming means to the other and de- 105 livering them in the same angular relation. 105
55. In an apparatus of the class described, means for successively forming work- 110 portions in alternately reversed relation, means for operating upon the formed portions, and means for transferring the portions from the forming means to the operating means and delivering them thereto in the same relation. 110
56. In a sole-making apparatus, means for cutting sole-portions with certain of the cut portions pointing in opposite directions, means for forming the cut portions while they are pointed in the same direction, and means for transferring the cut portions from the cutting means to the forming means and 115 for reversing some of said portions. 115
57. In a sole-making apparatus, a plurality of cutting members movable to bring different members into cutting position, and means for operating upon the cut portions, the cutting 125 members in their movement delivering the cut portions to the operating means and one of the cutting members being movable inde- 125 pendently of the associated cutting member to change its relation to the operating means. 130

58. In a sole-making apparatus, means for operating upon sole-portions, means for successively and alternately cutting sole-portions from sheet material with their corresponding ends extending in opposite directions, and means for successively delivering the sole-portions cut to the operating means with their ends in the same position with respect thereto.
59. In an apparatus of the class described, a plurality of revoluble cutting dies, one of said dies also being arranged to rotate.
60. In an apparatus of the class described, a plurality of revoluble cutting dies, one of said dies also being arranged to rotate, means for revolving the dies, and means for rotating the rotatable die during its revolution.
61. In an apparatus for making soles, a cutting abutment, a mold having the general contour of the surface of a shoe-bottom, and a die co-operating with and movable between the abutment and mold.
62. In an apparatus of the class described, a cutting abutment, a mold, a die co-operating with and revolving between the abutment and mold, and means for rotating the die during its revolution.
63. In an apparatus of the class described, a cutting abutment, a mold, a die co-operating with and revolving between the abutment and mold, means for moving the abutment and die relatively to effect the cutting, and means for moving the mold and die relatively to discharge the cut portion from said die.

FREDERICK H. PERRY.
